Des. 186,222
Patented Sept. 29, 1959

186,222

CONDUIT BOX UNIT OR SIMILAR ARTICLE

Leonard Atkin, Springfield, N.J., assignor to Stone Manufacturing Co., a corporation of New Jersey

Application July 15, 1958, Serial No. 51,779

Term of patent 14 years

(Cl. D26—5)

Fig. 1

Fig. 2

Fig. 3

Fig. 4

Fig. 5

Fig. 6

Figure 1 is a perspective view of a conduit box unit or similar article, showing my new design;

Figure 2 is a side elevational view;

Figure 3 is a top plan view;

Figure 4 is a bottom plan view;

Figure 5 is a front elevational view; and

Figure 6 is a rear elevational view thereof.

The broken line showing of a duplicate unit in position for ganging in Figure 1 is for illustrative purposes only.

I claim:

The ornamental design for a conduit box unit or similar article, substantially as shown and described.
